UNITED STATES PATENT OFFICE.

JOHN D. JONES, OF WALLA WALLA, WASHINGTON.

VALVE.

1,226,671.

Specification of Letters Patent.

Patented May 22, 1917.

Application filed February 1, 1915. Serial No. 5,459.

To all whom it may concern:

Be it known that I, JOHN D. JONES, a citizen of the United States, residing at Walla Walla, in the county of Walla Walla 5 and State of Washington, have invented certain new and useful Improvements in Valves, of which the following is a specification.

The present invention relates to improvements in valves and on my former Patent 10 No. 1,113,789, dated October 13, 1914, and has for its objects:

First, the provision of a valve having means for seating the valve within its casing when the same is both in its open and closed positions;

Second, the provision of means for moving the valve from its seat, during its movements from open to closed position or from 20 closed to open position, thereby preventing all wearing of the parts thereof, and greatly facilitating the quick and easy operation of the same;

Third, the provision of means for preventing 25 the entrance of dirt or foreign objects between the adjacent walls of the valve and casing and the valve and its seat;

Fourth, the provision of a valve wherein all operating parts are disposed without the 30 casing, thereby rendering them readily accessible, and easily replaced or repaired.

Fifth, the provision of a valve, which will be comparatively simple and inexpensive to manufacture, reliable and efficient in use 35 and readily operated.

With the above and other objects in view, the present invention resides in the novel features of construction, formations, combinations and arrangements of parts, to be 40 hereinafter more fully described, claimed and illustrated in the accompanying drawings, in which:

Figure 1 is a side elevation of a valve constructed in accordance with the present invention;

Fig. 2 is a longitudinal sectional view on the line II—II of Fig. 4 with the valve in its intermediate position;

Fig. 3 is a transverse sectional view taken 50 on the line III—III of Fig. 1; and

Fig. 4 is a similar view, taken on the line IV—IV of Fig. 1.

Referring to the accompanying one sheet of drawing, by corresponding characters of 55 reference throughout the several views, the

numeral 5, designates in dotted lines a portion of a boiler or the like, having an opening 6 therein, to which my improved valve 7 is applied.

This valve 7 comprises a valve casing 8 65 having a gradually tapered seat or bore 9 therein, and a flange 10, formed upon its inner or larger end, which engages the boiler 5, around the before mentioned opening 6. The flange 10, has one or more openings 11 65 provided therein for the reception of suitable fastening elements (not shown) whereby the valve 7 can be rigidly secured to the boiler 5. If desired a suitable packing, such as shown at 12, can be interposed between the 70 boiler 5 and flange 10, to prevent leakage. The valve casing 8, has an opening 13 formed in one side thereof which is preferably surrounded by an internally screw threaded nipple 14, to which can be attached 75 any suitable object such as a drain pipe or the like (not shown).

A cup valve 15 is located within the casing 8 and is externally tapered as shown to conform to the tapered bore 9 of the casing 8. The inner end of the valve 15, is open and communicates with the interior of the boiler 5, through the opening 6. The inner end of the casing 8 is channeled as at 16, to receive a thimble 17, which is provided with 80 an outwardly extending annular flange 18, designed to fit within the inner open end of the valve 15, thereby preventing the entrance of dirt or other foreign particles between the adjacent outer walls of the valve 90 15, and inner wall of the casing 8.

A stem 19 extends axially from the outer closed end of the valve 15, through an opening 20, formed in the outer closed end 21 of the casing 8, which is shown in Fig. 2 of the 95 drawing. There is a slight play or clearance between the opposite ends of the valve 15 and thimble 17, and closed end 21 of the casing 8, which permits of a slight longitudinal movement of the valve 15 for a purpose to be later explained.

Bosses 22 extend from diametrically opposite points upon the end 21 of the casing 8, while extending around the outer edge of this end 21, are arcual ribs 23 having cam faces 24 which curve inwardly from the bosses 22 to intermediate points between the said bosses, which are spaced a corresponding distance from the end of the casing 8. The opposite ends of the ribs 23 adjacent 110

the bosses 22 are spaced, likewise, a corresponding distance from the end of the casing 8.

A spider 25 is bolted or otherwise secured 5 as at 26 to the bosses 22 and is formed with inner cam faces 24', similarly curved and arranged to the cam faces 24 on the ribs 23; said cam faces 24 and 24' form guiding slots for purposes to be hereinafter explained. Said spider is also provided with 10 a central opening 27, through which the valve stem 19 extends, said opening 27 being slightly larger in diameter than the stem 19 to permit the insertion of a bushing 28 therein, which is keyed as at 30, to the said stem 19 in order that the same will be rotatable therewith. For the purpose of rotating the stem 19, the outer end thereof is made angular in cross-section as shown at 15 31, for engagement with a suitable tool or the like (not shown), by means of which the said stem 19 can be rotated and the valve moved either from open to closed position or from closed to open position, as desired.

25 Pins 32 project laterally from diametrically opposite points upon the sleeve 28 for insertion into the guiding slots and engagement with the cam faces 24 of the ribs 23, and cam faces 24' of the spider 25. When 30 the valve 15 is in its open or closed position, the pins 32 engage the cam faces 24 and 24' at the portions of the ribs 23, and spider 25 adjacent the bosses 22. Upon the movement of the valve from open to closed position, or 35 from closed to open position, the pins 32 will pass to the thinnest portion of the cam faces 24, as shown in dotted lines in Fig. 4, thus moving the outer end of the valve 15 farther away from the inner side of the wall 21, than when the valve is either in the open 40 or closed position, as indicated in dotted lines in Fig. 2.

It will be apparent that during this movement there will be no friction between the outer face of the valve 15 and its bore or seat 9 to cause any wearing of the parts, and owing to the absence of all friction, the valve can be easily rotated without the slightest exertion on the part of the operator. In order to further facilitate the easy 45 operation of the valve 15, a thin film of lubricant can be inserted between the adjacent surfaces of the valve 15 and bore or seat 9 in the casing 8.

50 To prevent the valve 15 from becoming unseated or disturbed from its open or closed position, the cam surfaces 24, 24' on the ribs 23 and the spider 25 and adjacent to the bosses 22, are preferably in a straight line as shown at 33, so that each of the pins 32, is resting on a plane flat surface and have no tendency to ride down or slide away from the extreme adjusted positions of the valve, should the boiler or section 55 of apparatus to which the valve is attached

be subjected to vibration, knocking or jar-ring action.

While I have shown and described my preferred valve construction, as being provided with the cam faces or guides 24 and 24', which coöperate with the two pins 32, this construction as shown, is not absolutely necessary to carry out the essential features of the invention. It will be readily seen from the foregoing disclosure of construction and operation, that when the valve is in position for use, and the internal section of the valve 15 is under pressure of the water, steam or other fluid, said pressure will normally tend to force said valve 15 against its seat or bore 9 or toward the closed end 21 of the casing 8 and either of the pins 32, connected to and moving with stem 19, will at all times, bear against one of the cam faces 24', and hence the valve 15, could be 25 slightly moved away from seat or bore 9 in the opening and closing of said valve as heretofore described, with only one pin 32 and one outer cam face 24', if so described.

It will also be seen that the cam faces 24 or 24' being on the outside can be readily machined or constructed, and put in position without necessitating the taking apart or removing the valve from the boiler or other apparatus.

It should be understood in this connection, that various minor changes in the specific details of construction can be resorted to within the scope of the appended claims, without departing from the spirit or sacrificing any of the advantages of the invention.

From the foregoing it will be manifest that a valve is provided, which fulfills all of the necessary requirements of such a device.

What I claim is:—

1. A valve comprising a casing, a valve rotatable therein for movement to and from its open or closed position, said valve being seated when in its open or closed position and unseated during movement to or from its open or closed position, a cam formed upon one end and exteriorly of the casing, a cam formed separately of and independently of the casing and arranged adjacent to the cam formed on the casing, a valve stem extending from said valve through the end of the casing, a sleeve keyed to the valve stem and a pin extending from the sleeve and engaging the cams formed independently of the casing, whereby upon the rotation of the valve stem, the valve will be moved from and to its seat during movement to and from its open or closed position.

2. A valve comprising a casing having an inlet and outlet, a hollow valve open at one end corresponding to the inlet of the casing and closed at the other end and rotatable

in said casing for movement to and from its open or closed position, said valve being seated when in its open or closed position by the pressure of the fluid entering the hole 5 valve through its open end and inlet of the casing, a valve stem extending from said valve through the end of the casing, a cam formed integral on said valve casing, an independent cam section separable from the casing and arranged adjacent to the cam formed on the casing, a pin on said valve stem engaging the cam on said valve casing and said independent cam section for moving said valve from its seat during its 10 movement to or from its open or closed position.

3. In a valve, a casing having a gradually tapered bore or seat therein, a gradually tapered hollow valve rotatable therein for 20 movement to and from its open or closed position, a stem extending from the valve through one end of the casing, said valve being seated against the end of the casing when in its open or closed position, a cam 25 provided upon one end of the casing exteriorly thereof, a spider secured to the casing adjacent the cam, and having a cam face corresponding to that on the casing, a bushing secured to the valve stem and 30 journaled within the spider and a pin formed upon the bushing and engaging the cams formed upon the casing and spider, whereby upon the rotation of the valve stem and valve, the latter will be moved from 35 and then to its seat.

4. In a valve, a casing having a gradually tapered bore or seat therein, a gradually tapered hollow valve rotatable therein for movement to and from its open or closed 40 position, a stem extending from the valve through one end of the casing, said valve being unseated against the end of the casing when in its open or closed positions, cam faces provided upon one end of the 45 casing exteriorly thereof, a spider secured to the casing adjacent the cams, and having cam faces corresponding to those on the casing, a bushing secured to the valve stem and journaled within the spider and pins 50 formed upon the bushing and engaging the cam faces formed upon the casing and spider, whereby upon the rotation of the

valve stem and valve, the latter will be moved from and then to its seat.

5. In a valve, a casing having a bore or 55 valve seat therein, a hollow valve open at one end and closed at the other and rotatable in the bore or seat in the casing for movement to and from its open or closed position, a thimble secured within one end 60 of the casing and fitting within open end of the valve, said closed end of the valve being unseated from the adjacent end of the casing in its open and closed, or intermediate positions, a stem extending from 65 the valve through one end of the casing, cams formed exterior of and upon one end of the casing, said cams being flattened at their ends, a bushing keyed to the valve stem, a spider secured to the casing exteriorly thereof, and forming a bearing for the bushing, said spider having cams upon 70 the inner side thereof conforming with the cams on the casing, and pins formed upon the bushing and engaging the cams on the 75 casing and spider and adapted upon the rotation of the valve to move said valve from and then to its seat either upon opening or closing the valve.

6. In valve, a casing having a bore 80 therein, a cam formed exterior of and upon one end of the casing, a hollow valve rotatable in the bore of the casing for movement to and from its open or closed position, a thimble secured within one end of 85 the casing and fitting within the hollow valve, a stem extending from the valve through one end of the casing exteriorly thereof, and forming a bearing for the bushing, said spider having a cam upon the 90 inner side thereof and forming with the cam on the casing a slot, and a pin formed upon the bushing and engaging the cams on the casing and spider whereby said valve upon rotation from its open or closed position is first raised and then forced upon its 95 seat.

In testimony whereof I affix my signature in presence of two witnesses.
